UNITED STATES PATENT OFFICE.

HENRY W. TAYLOR, OF RUGBY, ENGLAND, ASSIGNOR TO GENERAL ELECTRIC COMPANY, A CORPORATION OF NEW YORK.

HIGH-RESISTANCE CONDUCTOR FOR ELECTRICAL MACHINERY.

Application filed March 27, 1922. Serial No. 547,064.

To all whom it may concern:

Be it known that I, HENRY WILLIAM TAYLOR, a subject of the King of Great Britain, residing at Rugby, in the county of Warwickshire, England, have invented certain new and useful Improvements in High-Resistance Conductors for Electrical Machinery, of which the following is a specification.

10 In certain electrical circuits as for instance in rotors of inductor motors it is desirable that the conductors have a high resistance when carrying current at the normal frequency and a low resistance when carrying current at a low frequency.

In my United States Patent No. 1,487,286, I have described improvements in such conductors of the type in which the conductor consists of two sections, the space between the sections being nearly filled by magnetic material.

The object of my present invention is to provide further improvements in such conductors and consists essentially in the use 25 of more than two sections for such composite conductors, the space between the various sections being nearly filled with magnetic material.

More particularly I use such conductors 30 as the upper conductors in the arrangement of several multiple conductors as described in my aforementioned patent, and where for instance I use a conductor in accordance with my present invention consisting of 35 three parts I preferably make the upper and lower sections of a small sectional area, while I make the central section of a large sectional area.

The eddy currents which are induced in 40 such a conductor are confined to the outer sections and thus a greater multiplying factor is obtained at high frequencies than would be obtained if the whole of the sectional area of such a conductor were divided 45 as previously described in two sections only.

In the accompanying drawings which illustrate my invention, Fig. 1 corresponds to Fig. 2 of my patent above referred to, and shows a slot containing two composite conductors. Figs. 2, 3 and 4 show diagrammatically the manner in which I use composite conductors in accordance with the present invention in completed windings.

In Fig. 1 with two composite conductors A and B each consist of three sections; the outer sections *a* and *c* of the top conductor A, and *d* and *f* of the bottom conductor B being of high resistance while the central sections *b* and *e* are of low resistance.

The magnetizing effect of the bottom conductor B will produce a magnetic leakage across the magnetic spaces between the sections *a*, *b* and *c* of the top conductor A, and as the induced current in the upper conductor must circulate symmetrically it will not flow in the central low resistant section *b* but will flow around the high resistant outer sections *a* and *c* thus increasing the effective resistance of the whole winding at high frequencies.

It will be understood, however, that I do not confine myself to the use of similar constructed conductors at different positions in the slot and in the lowermost conductor of a slot containing many conductors, and more particularly in the lowest conductor of all I may not in certain forms of winding divide the conductor into more than two sections.

Fig. 2 corresponds approximately to the form of winding shown in Fig. 3 of my patent above referred to, in which for the sake of example I have shown a winding consisting of short circuited coils, the side of the coil corresponding to the upper conductor in the slot consisting of three sections of the type shown in Fig. 1, while the side of the coil corresponding to the bottom of the slot consists of two sections only. The distance between the dotted lines shown in Figs. 2 and 4 indicate the distance between consecutive poles.

Fig. 3 corresponds substantially to Fig. 7 of my patent above referred to, and in this figure I have shown a short circuited coil consisting of two complete turns, each conductor consisting of three composite sections, there being no electrical connection between the sections throughout the coil. In this winding I have arranged the order of connections between sections of various conductors in such a manner that the current generated between the outer section of the upper conductors by the magnetizing effect of the currents in the lower conductors becomes cumulative. This current flows only in the outer high resistant sections of the conductors.

tor, while the center section of low resistance has no such circulating current generated at high frequency.

Finally Fig. 4 illustrates a so-called squirrel cage type of winding in which the sections of the conductors from all slots are joined to common end bars at each end of the core. This figure corresponds to Fig. 8 of my patent above referred to.

10 What I claim as new and desire to secure by Letters Patent of the United States, is,--

15 1. A winding for a slotted core dynamo electric machine comprising two or more composite conductors per slot, each composite conductor containing more than two sections which are situated at different depths in the slot and separated from each other by a magnetizable medium, the outer sections of each composite conductor being 20 of higher resistance than an intermediate section thereof.

25 2. A secondary of a dynamo electric machine of the induction type comprising a slotted magnetic structure and a plurality of composite conductors at different depths in the slots, each composite conductor consisting of at least three sections at different

depths in the slot, the outer sections of said composite conductors being of higher resistance than an intermediate section.

30 3. A secondary of a dynamo electric machine comprising a slotted magnetic structure, a plurality of composite conductors at different depths in the slots, each composite conductor comprising at least three sections separated from each other and situated at different depths in the slot, the outer sections of said composite conductors being materially smaller in cross section than an intermediate section.

35 4. A secondary member of a dynamo electric machine of the induction type comprising a slotted magnetic structure, a plurality of composite conductors at different depths in said slots, each of said conductors comprising at least three sections at different depths in the slot, an intermediate section of the conductors being of smaller resistance than the outer sections, and end connections for connecting sections of different 40 conductors in closed windings.

45 In witness whereof, I have hereunto set my hand this seventh day of March, 1922.

H. W. TAYLOR.
